WILLIAM E. COOK, OF ST. GEORGE, NEW YORK, AND MERRITT B. BRADT, OF PENNINGTON, NEW JERSEY, ASSIGNEES TO PEERLESS INSULATED WIRE AND CABLE COMPANY, OF NEW YORK, N. Y., A CORPORATION OF DELAWARE.

INSULATED WIRE AND THE METHOD OR ART OF MAKING SAME.

Application filed November 20, 1917. Serial No. 203,055.

To all whom it may concern:

Be it known that we, WILLIAM E. COOK, a subject of the King of the United Kingdom of Great Britain and Ireland, residing at 5 St. George, in the borough of Richmond, city of New York, county of Richmond, and State of New York, and MERRITT B. BRADT, a citizen of the United States, residing at Pennington, in the county of Mercer and 10 State of New Jersey, have invented certain new and useful Improvements in Insulated Wire and the Methods or Art of Making Same, of which the following is a specification, reference being had therein to the accompanying drawing, which forms a part 15 thereof.

Our invention relates to insulated wire in which the electrical conductor is covered with a fibrous mass saturated or impregnated with an asphaltum or other waterproofing, insulating composition and a braid, and to the method or art of applying said fibrous material and said braid to the wire.

25 Heretofore insulated wires of the character above referred to have been extensively manufactured, the fibrous material, ordinarily cotton sliver, being spirally wound and compacted about the conductor wire and confined, while thus compacted so as to be at the desired density prior to the application of the braid thereto. In this type of wire, the braid serves more or less as a finish to the wire.

35 The method of producing a wire of the character above described consists in spirally winding a strip of fibrous material about a conductor wire, compacting this material, winding the wire so prepared upon 40 a spool, subsequently, by means of a braiding machine, applying the braid to this wire, and finally saturating or impregnating the wire with asphaltum or other similar composition.

45 In a wire made in accordance with our invention, we secure a mechanical bond between the fibres of the cotton sliver and the strands of the braid and utilize the braid as a confining means for holding the sliver 50 compacted preparatory to the application of asphaltum or other composition thereto, thus securing such permanency in the relation of the body of insulating material and

the braid upon same, as will minimize any tendency of the braid to strip from the wire 55 as the result of wear thereof.

Another characteristic of a wire made in accordance with our invention, is that the laid fibres of the cotton sliver, or other material, extend longitudinally of the wire by 60 reason of the fact that the strips of said material are laid upon the wire parallel thereto and subsequently wrapped about same in part by a forming die and in part by the application of the strands of this braid 65 thereto.

The method of producing a wire made in accordance with our invention is such as to permit the application of the cotton sliver, or other fibrous material, to the wire and of 70 the braid about said material, by a single and continuous operation. By this method, the strips of fibrous material are not subjected to those strains incidental to winding them spirally, and at high speed, about 75 the wire and likelihood of attenuation of the sliver, or other material, or breakage thereof is thus reduced to a minimum. Hence, by this method or art, it is possible to secure 80 substantial uniformity in the thickness of the insulation throughout the wire and substantial uniformity in the density of this insulation.

The invention consists primarily in an 85 insulated wire embodying therein a conductor wire, and insulation therefor consisting of a strip of lightly matted untwisted and unfelted fibrous material extending longitudinally of the wire, and a tubular braid covering and confining said fibrous material, 90 the outer fibers of said material being enmeshed with, or entangled in, the meshes of said braid, whereby said braid is imbedded in, and mechanically anchored to, said material, said material and said braid being impregnated with an electro non-conductive 95 and weatherproofing material bonding the fibers of said material and said braid together, and portions of said fibrous material overlaying portions of said braid, and in such other characteristics and in the novel steps and practices for producing said wire, all as hereinafter set forth and described, 100 and more particularly pointed out in the claims hereto appended.

105 In the accompanying drawing, there is

shown more or less conventionally, a short section of wire partly in elevation and partly in section, illustrating the essential characteristics of our invention.

5 In the embodiment of our invention shown in the drawing, *a* indicates the conductor wire which is inclosed by an insulating body of cotton sliver or other fibrous, absorbent material, formed of a plurality of strips, 10 two strips *b* and *c* being used in the form of wire illustrated in the drawing. These strips *b*—*c* are laid upon opposite sides of the wire, the fibres thereof being loosely laid and extending in a direction longitudinally 15 of said wire. The sole means for holding the strips *b*—*c* compacted about the wire is an ordinary braid *d* in tubular form, the strands of which are drawn tightly about the strips *b*—*c*, the outer fibres of said strips 20 being enmeshed or entangled in the meshes of the braid so that the braid is anchored at a multitude of points, directly to said fibrous coating. In practice, we have found that by so uniting the braid and the fibrous 25 material of the strips *b*—*c*, the braid is practically inseparable from the fibrous material, even before the covered wire is passed through the bath of asphaltum or other composition, so that likelihood of the loosening 30 of the braid at any point of the wire is obviated and separation of portions of the braid, even in the event of cutting from the abrasion thereof, is prevented.

35 In order to secure the desired enmeshment of the fibres of the strips *b*—*c* in the meshes of the braid, it is essential that the said strips shall not be compacted or confined by any medium other than said braid.

40 A wire made in accordance with our invention after the application of asphaltum, or other composition, thereof is smoothed, polished and burnished in the usual manner.

45 The application of asphaltum will not disturb the enmeshed or entangled fibres of the strips *b*—*c*, but will serve to increase the permanency of the bond thus created, by firmly cementing said fibres and said strands together.

50 In practice we have found it desirable to use two oppositely disposed strips of cotton sliver, or other absorbent material, of a width so that as these strips are folded together, the edges of one strip will lap the edges of the other and thus completely encircle the conductor wire. Ordinarily this strip is formed by folding the edges of a wider strip and lapping them so as to have the edges of the strip thinner than the central portion thereof. The fibres of the strips 55 are so loosely matted that after compaction, there is substantially no variance in the diameter of the mass of this fibrous material at different points thereof.

60 65 The number of strips used may be varied according to the desired thickness of the

insulation or the diameter of the wire to which the insulation is to be applied.

The method or art practiced in the production of a wire such as that above described, comprises the continuous feeding of 70 the conductor wire through a tubular braiding machine at low speed, simultaneously feeding a non-compacted strip or strips of cotton sliver, or other fibrous material, at the same speed as the wire is fed, and laying said strip or strips upon the wire with the fibres thereof extending longitudinally 75 of the wire. While the wire and the strip or strips are being thus fed, a plurality of strands of cord or thread are braided about the fibrous strip or strips, the loose meshes forming the braid, being brought in contact with the surface of the strips of fibrous material while they are uncompacted thus causing these meshes to pick up, or entangle 80 therewith, outer loose fibres of said material. Upon the subsequent closing of the meshes of the braid, the body of the fibrous strips will be compacted and formed about 85 the wire, and the previously enmeshed fibres of the material of said strips will be firmly clamped or held by the braid so as to form a firm interlock between said fibrous body 90 and said braid.

Upon the completion of the application 95 of the insulating material, including the braid, to the wire, we pass the covered wire through a bath of asphaltum or other composition, thoroughly saturating or impregnating the insulating material therewith in 100 a manner to make it weatherproof and increase its dielectric property. After the hardening of this composition, we form, polish and burnish the wire in the usual manner.

By laying the fibres of the cotton sliver or other similar material longitudinally of the wire, there is little or no tendency of the insulating covering to be unwound from the wire when stripping the wire during 110 installation.

The manner of applying the strips *b* and *c* is such as to relieve them of practically all stresses longitudinally thereof, thus avoiding attenuation of these strips, with a resultant thin spot in the insulation, or breakage of the strips, with a resultant loss of time in the operation of the apparatus.

From the foregoing it is apparent that the application of the body of insulating material and the braid covering therefor, is secured by substantially one and the same operation, thus permitting the complete covering of the wire by a continuous method, not only avoiding the necessity for employing complicated machinery for merely applying these strips to the wire preparatory to the application of the braid thereto, but also effecting a saving of the threads or cords ordinarily employed to hold the 125 130

fibrous material compacted upon the wire, while the braid is being applied thereto.

The entangling or enmeshing of the fibres with the interwoven strands of the braid, is secured by bringing these strands into engagement with the covered strips at one angle, and shortening this angle after engagement of the strips so as to maintain the strands in the proper relation to the fibrous material between the point of initial engagement of the strands therewith and the point of ultimate tightening of the meshes to secure the desired degree of compaction of the fibrous strips.

15 It is not our intention to limit the invention to the precise details herein shown and described, it being apparent that such may be varied without departing from the spirit and scope of the invention.

20 Having described the invention what we claim as new and desire to have protected by Letters Patent is:—

1. An insulated wire embodying therein a conductor wire, and insulation therefor consisting of a strip of lightly matted untwisted and unfelted fibrous material extending longitudinally of the wire, and a tubular braid covering and confining said fibrous material, the outer fibers of said material being enmeshed with, or entangled in, the meshes of said braid, whereby said braid is imbedded in, and mechanically anchored to, said material, said material and said braid being impregnated with an electro non-conductive and weatherproofing material bonding the fibers of said material and said braid together, and portions of said fibrous material overlaying portions of said braid.

40 2. An insulated wire embodying therein a conductor wire, and insulation therefor consisting of a strip of lightly matted untwisted and unfelted cotton sliver extending longitudinally of the wire, and a tubular braid covering and confining said cotton sliver, the outer fibers of said sliver being enmeshed with, or entangled in, the meshes of said braid, whereby said braid is imbedded in, and mechanically anchored to, said sliver, said sliver and said braid being impregnated with an electro non-conductive and weatherproofing material bonding the fibers of said sliver and said braid together, and portions of said cotton sliver overlaying portions of said braid.

45 3. An insulated wire embodying therein a conductor wire, a compacted, matted fibrous body inclosing same, the fibers of said body being laid substantially parallel with the axis of said wire, and a tubular braid covering and confining said fibrous material, outer

fibres of said material being enmeshed or entangled in the meshes of said braid.

4. An insulated wire embodying therein a conductor wire, a compacted, matted fibrous body inclosing same, the fibres of said body being laid substantially parallel with the axis of said wire, the fibres composing said strip being laid lengthwise thereof, and a tubular braid covering and confining said fibrous material, outer fibres of said material being enmeshed or entangled in the meshes of the braid.

5. The herein described method or art of making insulated wire consisting in laying a strip of non-compacted, loosely matted fibrous material upon a conductor wire, applying strands for forming a tubular braid to the exterior of said strip while it is still uncompacted, whereby said strand will be imbedded in said material, thereafter simultaneously closing the meshes of said braid and compacting said fibrous material whereby outer fibers of said material will be enmeshed with, or entangled in, the meshes of said braid, and portions of said fibers will be caused to overlay the strands forming said braid to mechanically anchor said braid to said material, and thereafter impregnating said material and said braid with an electro non-conductive and weatherproofing composition.

6. The herein described method or art of making insulated wire consisting in laying a noncompacted strip of matted fibrous material longitudinally of and upon a conductor wire, applying a tubular braid to the exterior of said strip while it is still uncompacted, and closing the meshes of said braid upon said fibrous material, while compacting same, whereby the fibres of said material will be laid substantially parallel with the axis of the wire, and outer fibres of said material will be enmeshed or entangled in the meshes of said braid.

7. The herein described method or art of making insulated wire consisting in laying a plurality of strips of noncompacted matted fibrous material longitudinally of and upon a conductor wire, applying a tubular braid to the exterior of said strip while it is still uncompacted, and closing the meshes of said braid upon said fibrous material while compacting same, whereby the fibres of said material will be laid substantially parallel with the axis of the wire, and outer fibres thereof will be enmeshed or entangled in the meshes of said braid.

In witness whereof, we hereunto affix our signatures this 29th day of October, 1917.

WILLIAM E. COOK.
MERRITT B. BRADT.
